UNITED STATES PATENT OFFICE.

FIELDER I. HISS, OF WILKINSBURG, PENNSYLVANIA, ASSIGNOR TO WESTINGHOUSE ELECTRIC AND MANUFACTURING COMPANY, A CORPORATION OF PENNSYLVANIA.

FIELD-COIL SUPPORT.

1,253,242.

Specification of Letters Patent. Patented Jan. 15, 1918.

Application filed September 28, 1912. Serial No. 722,973.

To all whom it may concern:

Be it known that I, FIELDER I. Hiss, a citizen of the United States, and a resident of Wilkinsburg, in the county of Allegheny and State of Pennsylvania, have invented a new and useful Improvement in Field-Coil Supports, of which the following is a specification.

My invention relates to dynamo-electric machines and it has special reference to the field coil structures of machines of the compound-wound type.

One object of my invention is to provide a structure of the above-indicated class which shall be simple and durable in construction and be readily assembled and dismantled, and one that shall be so constructed as to provide for adequate ventilation and liberal radiation.

Another object of my invention is to provide means for rigidly supporting the series coils of a compound wound dynamo-electric machine in position in such manner as to be entirely independent of the shunt coils.

In my co-pending application, Serial No. 5,98,519, filed December 21, 1910, by me and assigned to the Westinghouse Electric & Manufacturing Company, is disclosed a dynamo-electric machine of the compound-wound type embodying a plurality of main polar projections each of which is provided with a shunt field coil and a series field coil that are concentrically disposed with respect to the polar projection, the series field coil being taped or bound to the shunt field coil by suitable means to form a unitary structure. With such a structure, if the shunt field coil becomes defective, by reason of undue heating, it is necessary to remove the associated shunt and series coils and to disconnect and separate the one from the other.

According to my present invention, I propose to employ shunt and series coils which are disposed in substantially the same relation as that just referred to, and to support the series coil rigidly in position from the polar projection by suitable means in such manner that it shall be entirely independent of the shunt coil. Thus, the series coil may be readily and quickly removed for repairs or for other purposes without disturbing the shunt coil and the shunt coil may then be removed for the same purposes.

My invention may best be understood by

reference to the accompanying drawing in which Figure 1 is a view, partially in side elevation and partially in section, of a portion of a dynamo-electric machine constructed in accordance with my invention. Fig. 2 is a face view of one of the polar projections and its associated field coils shown in Fig. 1, said view being taken in the direction of the arrow II shown in the figure, and Fig. 3 is a face view of the interpolar projection and its associated field coil shown in Fig. 1, looking in the direction of the arrow III shown in the figure.

Referring to the drawing, the structure shown comprises a field magnet frame 1 having main polar projections 2 and interpolar projections 3, a shunt field coil 4 and a series field coil 5 disposed upon the main polar projection 2 and commutating field coil 6 disposed upon the interpolar projection 3.

The field magnet frame 1 and the polar projections 2 and 3 may be of any suitable form and dimensions, the polar projections 2 and 3 being detachably secured to the field magnet frame 1 by any suitable means. The main polar projection 2 is provided with projecting pole tips 7 and with a closed circuit winding or damper 8 which is embedded in the face of said member 2. However, these specific structures are not essential to my present invention, and may, therefore, be omitted or replaced by other similar devices, as desired.

The shunt field coils 4 are of like construction and each comprises a plurality of flat, thin coils 8^a which are assembled side-by-side and are spaced and insulated the one from the other by spacing members 9. The several flat coils 8^a are bound together to form a unitary structure by means of bands 10 of insulating material, said bands being located at frequent intervals around the coil, thereby permitting ample ventilation and radiation of heat. Although I consider shunt coils, constructed substantially as set forth, as preferable, for certain sizes and classes of machines, I do not wish to be restricted in this respect, as the specific structural details of these coils may be varied widely within the scope of my invention.

Each of the shunt coils 4 is placed upon one of the polar projections 2, and its inner end rests against the pole tips 7, while its outer end is spaced from the inner portion

- of the field magnet frame 1 by means of a plurality of insulating spacing members 11 which are attached to the shunt coils 4 in a suitable manner.
- 5 The series coils 5 are also of like construction, and each comprises a plurality of convolutions of strap conductor 12 which are spaced and insulated, one from another, by spacing members 13. The series coil 5 is of
- 10 somewhat greater mean diameter than the shunt coil 4, and is disposed concentrically with respect thereto. Moreover, the series coil 5 is materially shorter than the shunt coil 4 and is disposed adjacent to the field
- 15 magnet frame 1, being rigidly held in position in a manner to be hereinafter described, so that ample space for ventilation is provided between the series and shunt coils.

In order to mount the series coils 5 in position, each of the main polar projections 2 is provided with a plurality of supporting members or brackets 14 which are severally attached adjacent to the opposite sides of the polar projection 2 by means of one or

20 25 more bolts 15, or similar devices.

Each of the supporting members or brackets 14 is provided with inwardly projecting end portions 14* which have lugs 16 provided with open ended slots 17. The lugs 16 are in a plane substantially perpendicular to the axis of the polar projection 2 with which the bracket 14 is associated, and the slots 17 are adapted to receive an insulated bolt 18 which projects through openings in the several convolutions of the strap conductor 12 comprising the series coil 5, whereby said series coil is rigidly mounted in position independently of the shunt coil 4.

The commutating field coils 6 are substantially like the series field coils 5 in construction, and are mounted in position upon the interpolar projections 3 in a similar manner by means of a plurality of supporting members or brackets 18* and insulated bolts 19.

40 45 No detailed description of the structure of the commutating field coils and the supporting means therefor will be given on account of their similarity to the parts already

shown and described in connection with the series coils 5.

Although I have set forth a dynamo-electric machine of the compound-wound converter type which embodies interpolar projections and associated commutating field coils, it is, of course, evident that my invention is equally applicable to machines which are not provided with the interpolar projections and commutating poles. Furthermore, many modifications may be effected in the structural details and arrangement and 55 60 location of parts without departing from the spirit and scope of my invention.

I claim as my invention:

1. In a dynamo-electric machine, the combination with a field-magnet having a plurality of polar projections, a plurality of shunt field coils severally disposed thereon, and a plurality of series field coils severally surrounding said shunt field coils, of means attached to each of said polar projections for rigidly supporting the series field coils in position independently of said shunt field coils, whereby the said series coils are independently removable with respect to the said shunt coils.

2. In a dynamo-electric machine, the combination with a field-magnet frame having a plurality of radial polar projections, shunt field coils severally disposed upon said projections, series field coils surrounding said shunt field coils in concentric relation therewith, and means supporting said shunt coils, of a plurality of supporting members removably secured to each polar projection, and means associated with said members for 80 85 clamping said series coils in position, whereby the said series coils are independently removable.

In testimony whereof, I have hereunto subscribed my name this 21st day of Sept., 90 1912.

FIELDER I. HISS.
